UNITED STATES PATENT OFFICE.

JOHN GRIFFIN, OF BUFFALO, NEW YORK.

INGOT MOLD.

Application filed February 25, 1924. Serial No. 695,112.

To all whom it may concern:

Be it known that I, JOHN GRIFFIN, a citizen of the United States, residing at Buffalo, in the county of Erie and State of New York, have invented certain new and useful Improvements in Ingot Molds; and I do declare the following to be a full, clear, and exact description of the invention, such as will enable others skilled in the art to 10 which it appertains to make and use the same.

In molding ingots, a great many flaws often occur, when the molten metal is poured directly into the ingot mold, with the consequent splashing and violent agitation incident to such pouring. It is the object of my invention, however, to provide a mold having a separate pouring box into which the molten metal is poured from the ladles and, from which the metal overflows into the mold, in a gentle, smoothly flowing stream which will produce no violent agitation and splashing as it enters the mold, provision being made whereby the mold is 20 filled in a substantially horizontal position so that the metal does not have a great distance to descend from the pouring box.

The mold with which the improved pouring box co-acts, is provided with an open end with which said box is associated, and it is a further aim to so connect the box and mold as to permit the former to be swung aside after the two have been moved to substantially upright position, thus permitting access to the completed ingot, for removing the same with a hoist.

A further object of the invention is to provide the pouring box with an inner end which projects snugly into the open end of the mold, to establish an effective connection between the two.

With the foregoing in view, the invention resides in the novel subject matter hereinafter described and claimed, the description being supplemented by the accompanying drawings.

Figure 1 is a side elevation of an ingot mold improved in accordance with my invention, showing the position of parts when filling.

Figure 2 is a side elevation showing the mold in readiness for removing a completed ingot.

Figure 3 is a plan view, the parts being related as shown in Fig. 1.

Figure 4 is a vertical longitudinal sectional view as indicated by line 4-4 of Fig. 3.

Figure 5 is a vertical sectional view showing the mold and the pouring box swung to a vertical position.

Figure 6 is a horizontal sectional view on line 6-6 of Fig. 4.

Figure 7 is a detail perspective view of a portion of the pouring box.

Figure 8 is a vertical transverse sectional view as indicated by line 8-8 of Fig. 4.

In the drawings above briefly described, the numeral 1 designates an ingot mold, having an open upper end and downwardly tapered toward its closed bottom. To mount this mold for movement to and from vertical and horizontal positions, I have shown its sides provided with trunnions 2, rotatably mounted in bearings 3 on a pair of suitable supports 4. A horizontal rod 5 may be inserted between the mold 1 and the supports 4 to hold the latter in horizontal position after it has been moved to such position, for instance by a hoist 6. The supports 4 and the mold 1 may well be provided with hooks 7 rigidly carried thereby to engage the rod 5, so as to hold the mold against tilting in either direction when the molten metal is being poured.

For co-action with the open upper end of the mold 1, I provide a pouring box, designated in a general way by the numeral 8. In the construction shown, this box comprises a bottom 9 and a pair of sides 10 which abut the walls of the mold, at the open end of the latter, as shown most clearly in Figs. 4, 5 and 6. The box 8 also includes an outer end 11 joined to the sides 10 and bottom 9, and an inner end 12, the latter being preferably formed of fire brick or other refractory material, while the parts 9, 10 and 11 may be formed of metal and provided with refractory linings 13, of fire brick or the like. The end 12 projects beyond the inner edges of the bottom 9 and sides 10, as shown in Figs. 4, 5 and 6 and this projecting portion is snugly received in the open end of the mold 1 so as to form a tight connection between said mold and the box 8, and while the aforesaid end 12

may be secured in place in any desired manner, I prefer to provide the bottom 9 and sides 10 with inwardly turned flanges 14 received in grooves in the edges of said 5 end 12. Also, the sides 10 and end 11 may be formed with flanges 15 to assist in holding the linings 13 in place.

The box 8 is connected with the open end of the mold in a manner to swing bodily 10 therewith from the horizontal position of Fig. 4 to the vertical position of Fig. 5; and said box is then movable aside (see Fig. 2) so that the ingot within the mold 1 is accessible. In connecting the box and mold, 15 I have shown a pivotal connection which is preferably established in the following manner. I take a one-piece U-shaped stirrup 16 and weld or otherwise secure its intermediate portion across the bottom 9, 20 while its arms 17 extend along the sides 10 and are welded or secured in any other desired manner to the latter. These arms preferably incline toward the mold 1 and project beyond the box 8, the projecting ends being 25 pivoted at 18 to opposite sides of the mold. This stirrup will effectively support the box 8 in the position shown in Fig. 4 and will reinforce said box to a desirable extent, and the projecting ends of the arms 17 insure 30 that the box shall properly lie at one side of the mold, when the latter is moved to the position shown in Fig. 2.

To cast an ingot, the mold and box are positioned as shown in Fig. 1, with the latter adjacent a suitable pouring table 19. From this table, the molten metal is poured 35 into the box 8 and it will overflow from this box and pass over the comparatively low inner end 12 thereof, in a smoothly flowing, gentle stream; so that the metal enters the mold 1 without severe splashing in the latter or creating any violent eddies, such as those caused when the metal is poured directly into the mold from an open upper 40 end thereof. When the mold has been filled to the desired extent, the entire device is turned to the position shown in Fig. 5 and the box 8 will then completely drain into the mold, after which said box is swung 45 out of the way as shown in Fig. 2.

Excellent results may be obtained from the general association and construction herein disclosed and it may therefore be followed if desired, but within the scope of 50 the invention as claimed, numerous minor changes may be made.

I claim:

1. The combination with an ingot mold having an open upper end and mounted for 55 movement to a substantially horizontal position for filling; of a molten metal receiving box associated with said open end of the mold and having a continuous side wall, said box being adapted to overflow into said 60 mold, and means connecting said box with

said mold for movement bodily therewith to a substantially upright position, said means permitting movement of said box away from the mold to allow removal of the completed ingot. 70

2. The combination with an ingot mold having an open upper end and mounted for movement to a substantially horizontal position for filling; of a molten metal receiving box associated with said open end of the 75 mold and having a continuous side wall, said box being adapted to overflow into said mold when the box and mold are both horizontal and means pivotally connecting said box with said mold to permit the box to be swung away from the mold after both box and mold have been moved to a substantially upright position, said means connecting said box and mold for movement bodily 80 from horizontal to vertical position. 85

3. The combination with an ingot mold having an open upper end and mounted for movement to a substantially horizontal position for filling; of a molten metal receiving box associated with said open end of the 90 mold and comprising a bottom and sides abutting the walls of the mold, an outer end, and an inner end which projects beyond said bottom and sides and has its projecting portion snugly received in the open end of the mold; said box being adapted to overflow into the mold, and means connecting said box with said mold for movement bodily therewith to a substantially upright position, said means permitting movement of 95 said box away from the mold to allow removal of the completed ingot. 100

4. The combination with an ingot mold having an open upper end and mounted for movement to a substantially horizontal position for filling; of a molten metal receiving box associated with said open end of the mold and comprising metal bottom and 105 sides abutting the walls of the mold, a metal outer end, refractory linings for said bottom, sides and end, and a refractory inner end which projects beyond said bottom and sides and has its projecting portion snugly received in the open end of the mold; said box being adapted to overflow into the mold, and means connecting said box with said mold for movement bodily therewith to a substantially upright position, said means permitting movement of said box away from the mold to allow removal of the completed 110 ingot. 115

5. A structure as specified in claim 4; said bottom and sides having inturned flanges received in grooves in the edges of 120 said inner end. 125

6. The combination with an ingot mold having an open upper end and mounted for movement to a substantially horizontal position for filling; of a molten metal receiving box associated with said open end of 130

the mold and having a continuous side wall, to permit said box to be swung aside when said box being adapted to overflow into said mold, and a U-shaped stirrup extending under the bottom of said box and having its 10 arms inclined toward the mold, said arms projecting beyond the inner end of the box, and means pivoting said arms to the mold

In testimony whereof I have hereunto affixed my signature.

JOHN GRIFFIN.
